United States Patent

Des. 240,385
Patented July 6, 1976

240,385

CONTAINER COVER

James K. Pfleider, Anoka, Minn., assignor to Dart Industries Inc., Los Angeles, Calif.

Filed Jun. 11, 1973, Ser. No. 368,711

Term of patent 14 years

Int. Cl. D7—07

U.S. Cl. D7—131

FIG. 1

FIG. 2

FIG. 3

FIG. 4

FIG. 1 is a top plan view of a container cover showing my new design;

FIG. 2 is a side elevational view thereof;

FIG. 3 is a bottom plan view thereof; and

FIG. 4 is a vertical cross-sectional view thereof, taken along the line 4—4 of FIG. 1.

I claim:

The ornamental design for a container cover, substantially as shown.
